CRANKSHAFT GRINDING MACHINE

Jules Miesse, Brussels, Belgium

Application September 5, 1946, Serial No. 694,883
In Belgium September 29, 1945

6 Claims. (Cl. 51—131)

1

This invention relates to crankshaft grinding or truing machines and has for its particular object to design a machine of this type that would be of compact and inexpensive construction and such as would enable grinding operations to be effected in a shorter time.

According to the invention, the crankshaft grinding machine is so designed as to enable the crankshaft to be ground in a vertical position and comprises a standard having slidably mounted thereon a carriage balanced by a counterweight the said carriage carrying a transverse shaft having slidably mounted thereon and suspended for oscillatory movement thereon the grinding wheel carrier mechanism, a resilient locking device being provided for keeping the said grinding wheel carrier mechanism in its operative position and for enabling disengagement and re-engagement thereof from and into said position without disturbing the micrometer feed adjustment of the grinding wheel carrier mechanism.

According to a further feature of the invention, the vertical movement of the carriage may be effected through an optional geared down mechanism and a quick action mechanism.

One way of carrying the invention into effect will be hereinafter described with reference to the accompanying drawings in which:

Fig. 1 is a front elevation of the crankshaft grinding machine;

Fig. 2 is a sectional view along the broken line II—II of Fig. 1;

Fig. 3 is a front view, drawn to a larger scale of the carriage forming a part of the machine and having mounted thereon the grinding mechanism;

Fig. 4 is a fragmentary sectional view taken at an angle of 45° with respect to Fig. 3;

Fig. 5 is a detail view showing some of the constitutive parts of the grinding mechanism.

Fig. 6 is a side view of Fig. 3; and,

Fig. 7 is a plan view of Fig. 3.

In the drawings, the table 1 of a base 2 (Figs. 1 and 2) has pivoted thereto a horizontal circular plate 3 formed with a peripheral groove 4 for engagement of a V-belt 5 driven from the flywheel 6 of a motor 7. The latter is pivotally supported on a pin 8, the said motor being adapted to be locked on the said pin, in various angular positions by means of a bolt 9, thus providing for the adjustment of the tension of the belt 5.

The table 1 has formed therewith or otherwise secured thereto a standard 10 comprising a slide 11 having slidably mounted thereon a carriage 12 balanced by a counterweight 13 through the me-

2

dium of a chain 14 adapted to run over pulleys 15.

A second plate 16 guided in a diametrically extending groove 17 of the plate 3 is adapted to be locked in an eccentric position with respect to the plate 3. The plate 16 supports a rotary chuck plate 16' provided with locking means and adapted to receive the flange of a crankshaft 18 to be ground, the latter being secured to the rotary chuck plate 16' by bolts passing through holes 19 in the latter plate. The arrangement is such that when the crankshaft has been centred on the rotary chuck plate 16' the latter is in turn being locked to the plate 16.

Slidably mounted on the slide 11 is a head stock 20 adapted to be locked in a suitable position on the standard 10 and carrying a centre 21 adapted to engage the axial bore of the crankshaft whereby to hold the latter in position.

In a socket 22 arranged laterally of the base 2 there is secured a vertical column 23 having its upper end supported by an arm 24 extending from the top end portion of the standard 10. The column 23 has slidably mounted thereon a sleeve 25 provided with a locking handle 26, the said sleeve carrying a fork 27 adapted to sustain the work to be ground.

Slidable with easy friction on a transversely positioned tube 28 (Figs. 1, 3, 4), which has its ends secured to the carriage 12, there is arranged 30 a sleeve 29 rigid with a bracket 30, the latter having secured thereto the motor 31 adapted, through the medium of pulley 32 and belt 33, to drive a shaft the outer end of which carries the grinding wheel 34, the said shaft being rotatably mounted in a bearing 35 rigid with the bracket 30.

The grinding mechanism 29, 30, 31 constructed as shown, forms a pendulous assembly adapted to oscillate around the tube 28.

When grinding is being effected, the grinding wheel 34, while being caused to rotate at high speed under the drive of the motor 31, may perform in addition an angular displacement around the axis of the tube 28, which is obtained by the operator actuating a handle 36. Owing to such angular displacement, the grinding wheel may be completely disengaged from the portion of the work which is under grinding and, moreover, the grinding operation may be started by progressively engaging the periphery of the grinding wheel with a resulting highly smooth working contact.

The motor 31 is connected through a flexible cable 37 to a switchboard (not shown) secured 55 to the machine, the said switchboard controlling

in addition the motor 7 adapted to impart rotary movement to the plate 3.

The feeding mechanism whereby the position of the grinding wheel is adjusted with respect to the axis of the stock to be ground comprises a shaft 54 slidably mounted in the bracket 30 and adapted to cooperate with an abutment plate 55 rigid with the carriage 12. The shaft 54 is screw threaded and has formed therein a longitudinal groove 56 having engaged therein a guide key 57 rigid with the bracket 30.

In a recess 58 in the bracket 30 there is provided a tapped sleeve 59, said sleeve engaging the shaft 54 and having its ends abutted against the walls of the recess 58. The said sleeve has mounted thereon a pinion 60 adapted to cooperate with a worm formed on a shaft 61 journalled transversely in the bracket 30 and operated by means of a knob 62 provided with a movable dial furnished with resilient arresting means, the said dial co-operating with a fixed graduated scale provided on the mechanism.

A spring 63 having one of its ends attached to a ring 64 fixed to the carriage 12 (see more particularly Fig. 5), has its opposite end engaged by a bar 65 terminating in a pawl 66. The said pawl is adapted to engage one of a series of corresponding teeth of a rack 67 fixed to a laterally protruding portion of the bracket 30 (Fig. 6), the function of the spring and rack assembly being to press the shaft 54 resiliently against the abutment plate 55 on the carriage. At the rear of the pawl 66, the bar 65 is provided with a clevis 68, the clevis pin 69 being adapted to co-operate with a hook 70 formed on the end of a control lever 71 pivotally mounted at 72 onto the carriage 12.

When the lever 71 is shifted from left to right, the hook 70 is brought into engagement with the clevis pin 69 and retracts the pawl 66 out of engagement with the teeth of the rack 67. Stops 73 are adapted to limit the stroke of the lever 71 in either direction of movement. On the other hand, when the said lever is shifted from right to left—which is effective in the pawl 66 engaging one of the teeth of the rack 67, in accordance with the diameter of the stock to be ground—then, when the lever abuts against the stop 73, the end of the hook 70 comes to push against the bar 65, thus properly engaging the pawl into the rack teeth, so that the pawl 66 will be held correctly by the teeth.

The screws 74 by which the abutment plate 55 is fixed in place are provided with conical heads which act as stops adapted to limit the magnitude of pendulous movement imparted to the grinding mechanism by the action of the operator when the latter actuates the handle 36 for this purpose.

The above described feed mechanism for the grinding wheel makes it possible to effect the adjustment of the position of the grinding wheel 34 with respect to the axis of the stock to be ground, with accuracy. The aforesaid mechanism further enables the said grinding wheel to be quickly retracted from its operative position, which result is achieved through the actuation of the lever 71, which, by disengaging the pawl 66 from the rack 67, is effective in shutting out the action of the resilient locking device for the grinding mechanism, so that the sleeve 29 by which the latter is suspended on the carriage is able to slide on the shaft 28 when the operator applies a manual pull on the knob 48.

When the grinding mechanism is in the re-

tracted position, the operator is enabled to easily check the progress of the grinding work effected on the crankshaft 18, whereupon he may return the mechanism to the operative position in order to finish the grinding action, if necessary, said return being effected with the same swiftness as the retraction and being achieved by replacing the various parts into their initial position, the arrangement being such that the shaft 54, the adjustment of which has remained unchanged, returns to the position in which it bears against the abutment plate 55.

Vertical displacement of the carriage 12 along the guides 11 in the course of the grinding operation is normally effected by actuating the crank 49 which operates a shaft 75 carrying a worm 76 engaging a pinion 50 integral with a pinion 52 (Fig. 7), the latter pinion co-operating with a rack 53 fixed to the standard 10. The pinion 50 and the pinion 52 are keyed onto a shaft 51 journalled in the carriage 12 and adapted to be operated by a crank 77. The shaft 75, which is operable by the crank 49, is rotatably mounted in a housing 78 adapted to be rocked around a fulcrum pin 79 supported on the carriage 12. A rod 80 pivoted to the housing 78 and subjected to the action of a spring 81 tends to keep the worm 76 in constant mesh with the pinion 50.

Owing to the particular arrangement of the operating gear for effecting the vertical displacements of the carriage, as above specified, a fine adjustment of the feed of the said carriage may be obtained in the course of the grinding operation, which is achieved in operating the handle 49, while, on the other hand, the said carriage may be fed at a greater speed when it is required to change over from one crank pin to another or from one bearing surface to another.

In order to perform the high speed movement of the carriage, the operator will grip with his right hand the crank 49, pulling the latter downwards against the opposing action of the spring 81, which movement causes the housing 78 to be rocked around the fulcrum pin 79, thus disengaging the worm 76 from the pinion 50. Once the worm 76 has been disengaged from the pinion 50, the operator will actuate with his left hand the crank 77 which will operate the pinion 52 and will cause the displacement of the carriage in the desired direction until the new operative position is reached. The operator will then release the crank 49, thus allowing the worm 76 to return automatically into mesh with the pinion 50 under the action of the spring 81.

Owing to the vertical arrangement of the crankshaft in the device according to the invention, the counterweights required for balancing the crankshaft in a horizontally working device are dispensed with, thus allowing for a substantial saving in labour as far as the operation of placing the work in the grinding machine is concerned. Due to the elimination of counterweights, the rotation of the crankshaft is rendered more uniform and the work performed is more satisfactory.

Moreover, the position of stable equilibrium assumed by the crankshaft with the crankshaft flange acting as a base when the work is in position on the chuck plate of the grinding machine makes the centering operation easier and more expeditious.

Furthermore, the centring of the crankshaft with the object of grinding the crankpins with the crankshaft in the vertical position is also

greatly facilitated and rendered more expeditious by the provision of the plate 16 which is adapted to slide with respect to the plate 3.

What I claim is:

1. In a crankshaft grinding machine, a base, a horizontal rotatable plate on the said base, means on the said plate for centering and fixing the crankshaft to the ground in the vertical position, an electric motor supported by the said base, a V-belt transmission for connecting the said motor to the said plate, a standard secured onto the said base, vertical slides associated with the said standard, a head stock for being fixed in an adjustable position on the said slides and for supporting the end of the stock to be ground, a 15 sliding carriage on the said slides, a counterweight for balancing the said carriage, a linking member for connecting the said carriage to the said counterweight, means associated with the said carriage for operating the vertical movements of the latter along the said slides, a grinding device suspended for rocking motion on the said carriage, and means for moving the grinding device radially with respect to the axis of the stock to be ground.

2. In a crankshaft grinding machine, a base, a horizontal drive plate on the said base for centering, for securing and for driving the crankshaft in its vertical position, a standard secured onto the said base, slides on the said standard, a counterweighted carriage for sliding along the slides, means for operating the vertical displacements of the said carriage along the said slides, horizontal cylindrical guiding means associated with the said carriage and located radially with respect to the axis of the stock to be ground, a grinding device, a sleeve associated with the top portion of the grinding device for sliding movement on the said guiding means and for enabling the said grinding device to rock around the said guiding means, a grinding wheel shaft journalled in the said grinding device, an electric motor secured beneath the said grinding device, a belt transmission for connecting the said motor to the said grinding wheel shaft, means for adjusting the radial distance between the grinding device and the axis of the stock to be ground, resilient means for maintaining the said grinding device in its operative position, means for rendering the said resilient means inoperative, and means for imparting manually a limited rocking movement to the said grinding device.

3. In a crankshaft grinding machine, a base, a horizontal drive plate on the said base for centering, for securing and for driving the crankshaft in its vertical position, a standard secured onto the said base, slides on the said standard, a counterweighted carriage for sliding along the said slides, means for operating the vertical displacements of the said carriage along the said slides, horizontal cylindrical guiding means associated with the said carriage and located radially with respect to the axis of the stock to be ground, a grinding device suspended for rocking and for sliding movement on the said guiding means, a fixed abutment secured to the said carriage, a screw threaded shaft slidably mounted in the said grinding device for co-operation with the said fixed abutment, a tapped sleeve engaged upon the said screw threaded shaft and having both of its ends abutted in the said grinding device, a pinion secured around the said tapped sleeve, a worm journalled in the said grinding device for driving the said pinion, a knurled knob for operating the said worm, a resilient connection between the 75 support associated with the said plate for sliding

said grinding device and the said carriage for keeping the said screw threaded shaft in contact with the said fixed abutment provided on the carriage, and means for rendering the said resilient connection inoperative and for causing the said grinding device to slide on the said horizontal guiding device.

4. In a crankshaft grinding machine, a base, a horizontal drive plate on the said base for centering, for securing and for driving the crankshaft in its vertical position, a standard secured onto the said base, slides on the said standard, a counterweighted carriage sliding along the said slides, means for operating the vertical displacements of the said carriage along the said slides, horizontal cylindrical guiding means associated with the said carriage and located radially with respect to the axis of the stock to be ground, a grinding device suspended for rocking and for sliding movement on the said guiding means, a fixed abutment secured to the said carriage, an adjustable abutment provided on the said grinding device for co-operation with the said fixed abutment, a tension spring having one of its ends hooked to the 10 said carriage, a pawl carrying member hooked to the other end of the said spring, a rack integral with the suspended grinding device the said rack having one of its teeth normally engaged by the pawl on the said member, a clevis formed at the 20 back of the pawl on the said member, a pin in the said clevis, an operating lever pivoted in the said carriage, a hook on one end of the said lever for engaging the said clevis pin and disengaging the said pawl from the said rack when the 30 said operating lever is moved angularly in one direction and for re-engaging the said pawl of the said member in the said rack when the said operating lever is moved in the other direction for disengaging the said lever from the said clevis pin.

5. In a crankshaft grinding machine, a base, a horizontal drive plate on the said base for fixing and driving the vertically positioned crankshaft, a standard secured to the said base, slides associated with said standard, a counterweighted carriage for sliding along the said slides, a horizontal cylindrical guide associated with the said carriage and arranged radially with respect to the axis of the stock to be ground, a grinding device suspended for rocking with respect to and for sliding along the said guide, means for adjusting the radial distance between the said grinding device and the axis of the stock to be ground, resilient means for maintaining the said grinding device in the operative position, means for rendering the said resilient means inoperative and for causing the said grinding device to slide along the said guide, a rack provided along the slides of the said standard, a shaft supported in the said carriage, a pinion secured onto the said shaft for co-operating with the teeth of the said rack, an operating crank associated with the said shaft, a second pinion secured onto the said shaft, a rocking housing pivoted to the said carriage, a shaft journalled in the said housing, a crank handle for operating the said second shaft, a worm integral with the said second shaft for co-operating with the said second pinion, and a spring for acting on the said housing for maintaining the said worm in engagement with the 50 said second pinion.

6. In a crankshaft grinding machine, a base, a horizontal rotatable plate on the said base, a diametrically extending groove in the said plate, a 75 support associated with the said plate for sliding

in the said groove, means for securing the said support to the said plate, a second horizontal plate pivoted onto the said support, means for locking the said second plate with respect to the said support, an electric motor supported on the said base, a V-belt transmission for connecting the said motor to the first said plate, a standard secured to the said base, vertical slides associated with the said standard, a head stock for being secured in adjustable position on the said slides, and for supporting the upper end of the work to be

ground, a carriage slideable on the said slides, a counterweight for balancing the said carriage, linking means for connecting the said carriage to the said counterweight, means associated with the said carriage for operating the vertical displacements thereof along the said slides, a grinding device mounted for rocking motion on the said carriage and means for shifting the said grinding device radially with respect to the axis of the work to be ground.

JULES MIESSE.
